COMBINATION HOT AND COLD PACK

Joel Sisco, Passaic, N. J.

Application July 3, 1956, Serial No. 42,130

Term of patent 14 years

(Cl. D83—1)

Fig. 1 is a front elevational view of a combination hot and cold pack embodying my new design in its open position; and

Fig. 2 is a plan view thereof in folded position.

The characteristic feature of my design for the combination hot and cold pack disclosed resides in the pattern of ribbing appearing at the juncture of the end portions of the pack with the straps, as shown.

The rear, not shown, is the same as the front, shown.

I claim:

The ornamental design for a combination hot and cold pack, as shown and described.
